Primary Examiner — Wendy L Arminio*(74) Attorney, Agent, or Firm* — Michael Best & Friedrich LLP(57) **CLAIM**

I claim the ornamental design for a lantern, as shown and described.

DESCRIPTION

FIG. 1 is a front perspective view of a lantern in accordance with the present invention.

FIG. 2 is a left side view of the lantern of FIG. 1.

FIG. 3 is a right side view of the lantern of FIG. 1.

FIG. 4 is a front view of the lantern of FIG. 1.

FIG. 5 is a rear view of the lantern of FIG. 1; and,

FIG. 6 is a top view of the lantern of FIG. 1.

The portions of the lantern shown in broken lines having unequal length segments illustrate the boundaries of the claim and form no part of the claimed design. The remainder of the broken lines show portions of the lantern which form no part of the claimed design.
